CLAIM

The ornamental design for a toe straightener as shown and described.

DESCRIPTION

FIG. 1 is a front, right and top perspective view of a toe straightener, showing my new design.

FIG. 2 is a rear, left and top perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 1; and,

FIG. 10 is a front, right, top perspective view of the toe straightener of FIG. 1, shown exploded for clarity of disclosure.

The dot-dash broken lines in FIGS. 1 and 9 depict the boundaries of the enlargements and form no part of the claimed design.

1 Claim, 10 Drawing Sheets(56)
